UNITED STATES PATENT OFFICE.

ERNEST W. ASHENDEN, OF MINNEAPOLIS, MINNESOTA, ASSIGNOR TO WILLIAM BROS.
BOILER & MFG. CO., OF MINNEAPOLIS, MINNESOTA.

BAFFLE WALL.

Application filed October 16, 1926. Serial No. 142,108.

This invention relates to improvements in baffle walls as attachments for furnaces.

Objects are to provide means for converting an updraft furnace into a furnace capable of burning soft coal economically and smokelessly; to provide a baffle wall across the firebox of a locomotive boiler, said baffle being composed of segments suspended for rotation, to permit access to the boiler tubes for purposes of cleaning or inspection, and to change conditions of draft; to provide a baffle wall composed of independently suspended rotatable sections aligned or alignable transversely of the firebox to form a substantially solid wall, and having the lower ends arranged above the grate, to force gases downwardly into the fuel bed and obtain substantially smokeless combustion when using non-cooking coal; to provide suspending means whereby each segment can be independently removed, the said means acting to prevent accidental displacement when the segment is pendants disposed in baffle-forming position but permitting a segment to be removed when the same is raised toward a horizontal position.

Features of the invention include the detail construction of each part; the suspended rotatable arrangement of the baffle section, to permit rotation about the vertical axis of suspension; and the arrangement and construction of the means for suspending the elements and for permitting them to be separately removed.

Figure 1 is a vertical longitudinal section of a locomotive boiler showing my invention applied thereto;

Figure 2 is a vertical transverse section on the line 2—2 of Figure 1 showing the baffle sections in co-planar relation;

Figure 3 is a detail section on the line 3—3 of Figure 5 showing how a section is suspended;

Figure 4 is a fragmentary vertical sectional view taken approximately on the line 4—4 of Figure 1;

Figure 5 is a vertical section corresponding to Figure 1, but enlarged to show the details;

Figure 6 is a fragmentary top plan view of the supporting element showing the sockets and slots intersecting the sockets;

Figure 7 is a top plan view of one of the baffle segments.

The device has been shown applied within

the firebox of a locomotive boiler, the boiler being generally indicated at 1, the tubes at 2, the firebox at 3 and the grate at 4. Arranged transversely of the firebox and attached to the top wall thereof, is a baffle element-supporting structure 5 comprising in this instance a curved iron having a rear flange 6 arranged horizontally and traversed by bolts 7 to secure it to the arch of the firebox. The element further has a depending portion 8 terminating in a horizontal portion 9 in which are formed sockets 10, see Figure 3, the said sockets being preferably spherical. Each socket is cut by a slot 11 which extends inwardly from the forward edge 12 of the supporting element 5, each socket being thus open at one side. The supporting element is preferably in the form of a casting and in this instance is curved, although it will be understood that the same may be straight, to conform to a correspondingly shaped crown sheet. In this instance, the lower edge of the supporting element 5 is also curved, but it will also be understood that this may be straight. However, the curved formation is the ordinary one and it will be noted that the suspended baffle elements, now to be described, may be rotated, even though the lower edge of the suspending element may be curved. The spherical formation of the sockets permits the suspending elements to be moved from a vertical to a horizontal position and the arrangement is such that only when the baffle approaches a horizontal position, can it be removed.

A plurality of baffle elements are ordinarily employed although one may be used if desired. Each element is substantially identical, except where the supporting member is curved, in which case the tops of the elements may be differently angularly related to the vertical side portions thereof. Each element substantially comprises a body portion 15 having sockets 16 for the introduction of a tool to rotate the baffle element. At the top of the element, centrally thereof, is a projection or shank 18 having a spherical head 19 at its top adapted to fit within a socket 10. The shank 18 is of a diameter to lie loosely or rotatably within the slot 11 as shown in Figure 3. The lower ends of the elements may be either curved or straight, see respectively Figures 2 and 4. It will be seen that the segment is rotatable

about a vertical axis at the point of suspension, and it will be further noted that the sockets and the segments are of such width, and are so spaced that the segments may 5 be aligned or caused to assume a co-planar relation transversely of the firebox. By referring to Figure 1, it will be seen that any segment can be removed from its corresponding socket by being swung upwardly toward 10 a horizontal position, and the arrangement herein is such that the segment can only be removed when it reaches a point adjacent the horizontal plane. It will be noted that any segment can be removed, by being swung 15 toward the door.

I claim as my invention:

1. A baffle wall for the purpose described, composed of a plurality of suspended, adjacently disposed, segments, each segment being rotatable about a vertical axis at point of suspension, said segments adapted to be aligned in co-planar relation, to form a substantially imperforate wall.
2. A baffle wall for the purpose described, composed for a plurality of segments, suspended by their tops, each segment being rotatable about a vertical axis at point of suspension, said segments being alinable to form a substantially imperforate wall.
3. A baffle wall composed of a plurality of suspended segments each being rotatable about a vertical axis at point of suspension, said segments being alinable to form a substantially imperforate wall.
4. In combination, with a boiler having tubes, a fire door, and a fire chamber, a supporting plate secured transversely of the chamber between the tubes and fire door, said plate having a plurality of spaced 40 sockets opening in direction of the door, a plurality of segments each having a head resting within the socket to suspend and dispose the segments for rotation about a vertical axis, said segments adapted to be removed from said sockets by being swung 45 toward a horizontal position, in direction of the door.
5. In combination, a fire chamber, a supporting plate secured within the chamber 50 transversely at the top, and having a plurality of spaced sockets therein opening toward the front of the chamber, and a plurality of segments each having a head resting and rotatable within a socket.
6. In combination, a fire chamber, a supporting plate secured to the top wall of the chamber therewithin, and having a plurality 55 of spaced sockets, a plurality of segments each having a head resting within a respective socket and adapted to swing about a

vertical axis, said sockets open at one side to permit any segment to be removed when swung toward a horizontal position.

7. A device of the class described comprising a supporting structure having spherical sockets therein, each socket having a slot cutting the same vertically and extending inwardly from the front edge of the structure, a plurality of vertical segments each having a spherical head within a socket, to suspendingly support the segments for rotation about a vertical axis, said sockets and slots being so arranged that the head can be disengaged from the socket only when the segments are swung upwardly towards and are 70 approaching a horizontal position.

8. A device of the class described comprising a supporting structure having a spherical socket therein, said socket open at one side, a segment having a spherical head within the socket, to suspendingly support the segment for rotation about a vertical axis and permit it to be disengaged from the socket only when swung upwardly towards a 80 horizontal position.

9. A supporting plate for the purpose described having a plurality of spaced sockets therein, said sockets being open at one side, and an opening at the same side of said plate.

10. A baffle element for the purpose described having a shank centrally of its top side, said shank terminated by a spherical head, having its convex side facing toward the element.

11. In combination a boiler having tubes, a fire chamber, and a fuel door for the chamber, and a baffle wall within the chamber transversely thereof, between the tubes and door and composed of a plurality of segments suspended from the top of the chamber each rotatable about a vertical axis only at a point of suspension, said segments being normally alined in coplanar relation to form a substantially imperforate wall.

12. In combination a boiler having tubes, a fire chamber, and a fuel door for the chamber, and a baffle wall within the chamber transversely thereof, between the tubes and door, said wall composed of a plurality of segments suspended from and having their upper edges immediately adjacent the top of the chamber each rotatable about a vertical axis, only at a point of suspension, said segments being normally alined in coplanar relation to form a substantially imperforate wall, entirely across the chamber.

In witness whereof, I have hereunto set my hand this 14th day of October, 1926.

ERNEST W. ASHENDEN.
